Melvin Spitalny, Elizabeth, N. J., assignor to Volupte, Inc., Elizabeth, N. J., a corporation of
New Jersey

Application February 2, 1948, Serial No. 144,222

Term of patent 14 years

(Cl. D86—10)

To all whom it may concern:

Be it known that I, Melvin Spitalny, a citizen of the United States, residing at Elizabeth, in the county of Union and State of New Jersey, have invented a new, original, and ornamental Design for a Vanity Case, of which the following is a specification; reference being had to the accompanying drawing, forming part thereof.

Fig. 1 is a front elevational view of a vanity case, showing my new design.

Fig. 2 is a top plan view thereof.

Fig. 3 is a bottom plan view thereof.

Fig. 4 is a side view thereof.

Fig. 5 is a perspective view of the vanity case, as it appears in open condition.

I claim:

The ornamental design for a vanity case, substantially as shown.

MELVIN SPITALNY.
